UNITED STATES PATENT OFFICE.

EUGÈNE COLLON, OF CANNES, FRANCE.

FOLDING-MACHINE.

SPECIFICATION forming part of Letters Patent No. 703,546, dated July 1, 1902.

Application filed February 5, 1901. Serial No. 46,103. (No model.)

To all whom it may concern:

Be known that I, EUGÈNE COLLON, engineer, a citizen of the Republic of France, and a resident of 9 Rue de Cronstadt, Cannes, 5 Alpes-Maritimes, France, have invented certain new and useful Improvements in Folding-Machines; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

15 This invention refers to improvements in machines for folding table-napkins and other articles of linen or the like, (forming the subject of my United States Patent No. 677,436, dated July 2, 1901,) wherein the napkin (or 20 other article to be folded) having been put in motion by a cylinder which is provided with a continuous rotary motion is brought in contact successively with as many folding devices as it is to receive folds in one direction, 25 each of these devices folding it once. It then passes to another cylinder, which brings it into contact, with a second series of folding devices with the object of folding it in the other direction.

30 In machines of this kind each of the folding devices comprises a plate-guide supported against the cylinder in such a manner as to guide the linen goods therefrom, a knife having an intermittent movement to and from 35 the end of the plate and cylinder, and a creasing-roller below the plate.

The improvement consists in devices to move the plates, and to this end I operate them from the same mechanism that actuates 40 the knives, for which purpose I use a single cam-wheel.

A further improvement consists in mechanism to positively move the material to be folded into engagement with the cylinder at 45 a predetermined time, and the movements of the plates and knives are timed in accordance therewith.

The invention consists, further, in details 50 of construction and combinations of parts hereinafter fully described, and particularly pointed out in the claims.

Referring to the drawings, in which like parts are similarly designated, Figure 1 of the accompanying drawings represents in side elevation the arrangement of the first cylinder and of the parts of the apparatus surrounding said cylinder. Fig. 2 is a detail view, also in side elevation, of certain of the parts in different positions from those shown in Fig. 1; and Fig. 3 is a front elevation to a smaller scale, showing the general arrangement of the apparatus.

The principal parts of the machine consist of two standards 29 and 30, which are suitably tied or connected together. On these standards are fixed two smaller standards or frames 31 and 32, and between these is arranged the carrier-cylinder *b*, which is covered with a layer of felt 19, the shaft *y* of said cylinder being mounted in bearings 33. On 55 said shaft *y* are keyed, first, a disk *x*; secondly, a second disk 11, provided with cams *s*, *o*, and *h*, which are capable of adjustment by reason of their being arranged as follows: Each of these cams is provided with a tail-piece or lug 34. The lug 34 of the cam *o* takes into a recess 35, made in the disk 11, and the lugs 34 of the cams *s* and *h* are merely applied to the external and internal faces, 60 respectively, of the disk. These different 65 cams are fixedly attached to the disk by means of bolts 36 and fly-nuts 37, the slots 38, through which the bolts pass, permitting of varying the relative positions of the various cams. Supports 39, fixed in the frames 70 31 and 32 or cast in one therewith, support a fixed feed-table *c* and serve as bearings for a transverse shaft 40. On this shaft are fixed, 75 outside of the frames 31 and 32, two arms or levers 42, carrying a roller *v*, capable of revolving freely. On the same shaft is keyed a lever *w*, carrying a roller 41, and fixedly mounted on the said shaft are two lateral arms 43, connected by a rod *t*, which forms a counterweight to keep the roller 41 pressed 80 against the cam *x*.

The pressure-rollers *a*, *f*, and *l* are arranged between the frames 31 and 32, and as these three rollers are mounted in the same manner I will merely describe the arrangement of one of them. The roller *a* is provided with a shaft 44, each end of which runs in a bear-

ing 45, which slides in the slot or guides 102, formed between the two uprights of the frames. This roller is kept in contact with the carrier-cylinder *b* by means of springs *u* acting on the bearings 45. The tension of these springs is regulated by turning the screws 101, which pass through the screwed caps 103 on top of the slots or guides 102 and which press on the springs.

10 Between the frames 31 and 32 are arranged knives *e* and *k*, mounted, respectively, on slides 49 and 56, which are movable in the guides or slots 50 and 57, arranged in each of the said frames. The slides 49 are each provided with a pin or stud, (marked, respectively, 48 and 48'), which pins project outwardly and take into the slots, such as 47, formed at one end of each of the double-armed levers *p p'*, mounted, respectively, on the frames 32 and 31. The knife *k* is connected in the same manner by the studs 55 and 55' to similar levers 53 and 53'. The levers *p p'*, pivoted to the frames 31 32 at 200 201, are similarly provided at the other ends with slots through which pass the studs *q* and *q'*, fixed in the levers *r* and *r'*, which are keyed on a transverse shaft *d'*, mounted in the frames 31 and 32. The levers 53 and 53', pivoted to the same frames at 202 203, are connected in the same manner by slots and studs 58 and 58' to the levers *g* and *g'*, which are keyed on the transverse shaft *j'*. The lever *r* is prolonged to carry at its free end a roller 51, which rests on the disk 11 in the plane of the cam *s*. The lever *g* is prolonged in the same manner to carry at its free end a roller 104, which rests on the disk 11 in the plane of the cam *o*.

15 The supports 52 of a platform *d* are keyed to the shaft *d'*, which platform at its inner end is provided with a part 105, turned under in such manner that when the roller 51 rests on the periphery of the disk 11 this part 105 is quite close to the cylinder *b* and concentric therewith. The shaft *j'* also carries 20 a platform *j*, similar to the platform *d*.

25 A lever *6* is keyed on a transverse shaft 4 and has at one end a roller 60, which rests on the disk 11 in the path of the cam *h*. This shaft 4 is provided with two levers 3 and 3', which support the bar 62, on which is fixed the platform or leaf 1, and mounted on the same shaft 4 is a lever 8, jointed at the other end to a connecting-rod 9, of which the other end is connected to a lever 5, mounted loosely 30 on the shaft *y*. A similar lever 5' is mounted in the same manner at the other end of the shaft *y*, and these two levers are connected by a transverse rod 66, on which is fixed the platform or leaf 2.

35 Under the cylinder *b* is mounted a moving table or conveyer *i*, which receives the napkins folded in one direction around the cylinder *b* and conducts them to a second cylinder *b'*, similar to the one marked *b*, hereinbefore described, and for the purpose of folding the napkins in the other direction. This conveyer is constructed in the form of an endless

40 belt or apron *i*, which passes over a drum 67, and the cylinder *b'*, which are mounted in the frames 29 and 30 in such a manner that their 45 shafts are arranged at right angles to that of the cylinder *b*.

45 As shown in Fig. 3, the cylinder *b'* is provided with mechanism arranged to produce folding similar to that of the cylinder *b*— 50 namely, a disk 110, like the disk 11 and provided with cams *O* and *S*, similar to the cams *o* and *s*, two folding-knives operated by levers *R* and *P*, similar to the levers *r* and *p*, and levers *G* and 530, similar to the levers *g* and 53, two platforms *D* and *J*, similar to the platforms *d* and *j* and connected to the levers *R* and *G* in the same manner as the levers *d* and *j* are connected to the levers *r* and *g*, three rollers *A*, *F*, and *L*, similar to the rollers *a*, *f*, and *l* and arranged in the same manner. The napkins folded in both directions drop onto an endless moving table or apron *m*, which carries them a certain distance, wherefrom they are taken to be put in piles. The apron *m* passes over pulleys or rollers 79 and 80, the shafts of which are mounted in bearings 109 and 108, respectively, carried on lateral supports, such as 107, forming part of the framework of the machine. 90

49 All the moving parts are operated by means of the following arrangement: On the frame 29 are fixed brackets 65, carrying bearings 69, in which is mounted a shaft 22, and on this shaft is keyed a pulley 23, driven by a belt 71. 100 A bevel-wheel 21 (indicated in dotted lines on the said shaft) gears with and communicates motion to a bevel-wheel 20, keyed on the shaft *y* of the cylinder *b*, and, finally, a sprocket-wheel 70 on the shaft 22 drives a 105 sprocket-wheel 27, mounted on the shaft 73 of a drum 67, by means of a chain 72. This shaft 73 has keyed thereon a sprocket-wheel 26, which by means of a chain 74 communicates motion to a sprocket-wheel 75, keyed 110 on the shaft of the cylinder *b'*. There is also a sprocket-wheel 76 keyed on the shaft of the cylinder *b'*, which communicates motion to a sprocket-wheel 78, keyed on the shaft of the roller 79 by means of a chain 77, and consequently imparts motion to the endless apron or belt *m*. 115

54 The operation is as follows: The napkin to be folded is put on the platform *c* and is pushed in such manner that its end goes past 120 the platform and rests on the cylinder *b* at about the point *z*. (See Fig. 1.) The cam *x* comes into contact with the roller 41, and thus causes the lever *w* to swing, whereby the roller *v* presses against that part of the napkin underneath it. The napkin is consequently pressed against the covering of the rotary cylinder *b*, is caused to advance, and is fed under the roller *a*, which, pressed down by the springs *u*, forces the napkin into such 125 intimate contact with the cylinder *b* that the said napkin is constrained to move with the cylinder. At this moment the projecting part of the cam *x* passes by and releases the lever 130

w, which assumes its first position, as shown in the drawings, by reason of the counter-weight *t*. In advancing the napkin passes onto the platform *d*, and when a third of its length is thereon the cam *s* passes under the lever *r* and raises it, together with the platform *d*, which is mounted on the same shaft *d'* as the said lever *r*. At the same time the studs *q* and *q'* of the levers *r* and *r'* operate the levers *p* and *p'*, which latter cause the movement of the knife *e* and make it mark the fold. When the cam *s* has released the lever *r*, the latter, together with the knife *e* and the platform *d*, assume their original positions in such manner that the turned-under part 105 of the platform nips the fold formed and presses it against the cylinder *b*, which continues to carry with it the napkin thus once folded. The fold then passes under the roller *f*, which under the action of its springs presses the fold and, together with the cylinder *b*, serves to cause the napkin to advance onto the platform *j*. When the time arrives to form the second fold, the cam *o* raises the lever *g* (which acts exactly in the same manner as the lever *r*) for the purpose of raising the platform *j* away from the cylinder *b* and for lowering the knife *k*. The latter is then immediately raised, the platform *j* assumes its original position, nips the napkin for the second fold, and the napkin folded in three passes under the compressing-roller *l* and then falls to the receiving platforms or plates 1 2. The napkin slides on the platform or plate 1, and a certain portion slides onto the platform or plate 2. At the proper moment the cam *h* comes into contact with and depresses the roller 60, carried at the lower end of the lever *g*, which then swings and carries with it the levers *3* and *3'*, and the platform 1 thus swings away from the cylinder *b*, as shown in Fig. 2. The lever *8*, connecting-rod *9*, and arms *5* are also simultaneously actuated and moved into the position shown in Fig. 2, the plate 2 serving to positively strip the folded napkin from the cylinder *b* in case it should not fall therefrom by its own weight. The napkin then falls onto the endless belt or apron *i*, which carries it to the second cylinder *b'*. The napkin is carried around this cylinder in the same manner as it was around the first one, and it is folded in the other direction as compared with the folding performed by the first cylinder. The napkin then falls onto the endless band or apron *m*, from which it is taken by an operator, who piles the napkins.

It will be understood that in case the linen has only to be folded in one direction the second cylinder and the parts appertaining thereto may be dispensed with.

Having thus described my invention, what

I claim as new therein, and desire to secure by Letters Patent, is—

1. In a machine for folding linen, the combination with a rotating cylinder, guide-plates, folding-knives, and levers to actuate said plates and knives; of a cam-wheel rotating with said cylinder to actuate said levers, and means timed to move the piece to be folded into engagement with the cylinder, 70 substantially as and for the purpose set forth.

2. In a machine for folding linen, the combination with a shaft, a cylinder secured thereto, guide-plates, folding-knives, and levers to actuate said plates and knives; of a cam-wheel secured to said shaft to actuate the levers, and adjustable cam-surfaces on the wheel, substantially as and for the purposes set forth. 75

3. In a machine for folding linen, the combination with a shaft, a cylinder secured thereto, guide-plates, folding-knives, and levers to actuate said plates and knives; of a cam-wheel secured on the shaft to actuate said levers, a fixed table, a roller normally 85 out of engagement with the cylinder, and a cam on said shaft to cause said roller to move in front of the table to feed the piece to be folded to the cylinder, substantially as and for the purposes set forth. 90

4. In a machine for folding linen, the combination with a shaft, a cylinder secured thereto, guide-plates, folding-knives, and levers to actuate said plates and knives; of a cam-wheel secured to said shaft, cam-surfaces 95 adjustably secured thereto to actuate the levers, a plate, 1, a stripping-plate, 2, mounted to rotate around said shaft and cylinder, cam-operated lever mechanism to simultaneously actuate both of said plates 1 and 2, and cam-operated means to positively move the piece to be folded into engagement with the cylinder, substantially as and for the purposes set forth. 100

5. In a machine for folding linen, a shaft, 105 a bevel-wheel, a cylinder thereon, guide-plates, folding-knives, and levers to actuate said plates and knives; of a cam-wheel on said shaft, adjustable cam-surfaces thereon to actuate the levers, a counter-shaft, a bevel-wheel to mesh with the aforementioned one, an endless carrier-apron driven from the counter-shaft beneath said cylinder, and similar means to fold linen at its end, substantially as and for the purposes set forth. 110 115

In testimony that I claim the foregoing as my invention I have signed my name in presence of two subscribing witnesses.

EUGÈNE COLLON.
